CLAIM

The ornamental design for an adjustable maternity gown, as shown and described above.

DESCRIPTION

FIG. 1 shows a front elevation view of the adjustable maternity gown having a design in accordance with the present invention;

FIG. 2 shows another front elevation view of the bottom and top portions of the adjustable maternity gown in a separated condition having a design in accordance with the present invention;

FIG. 3 shows a back elevation view of the adjustable maternity gown having a design in accordance with the present invention;

FIG. 4 shows another back elevation view of the bottom and top portions of the adjustable maternity gown in a separated condition having a design in accordance with the present invention;

FIG. 5 shows a right elevation view of the adjustable maternity gown having a design in accordance with the present invention;

FIG. 6 shows another right elevation view of the bottom and top portions of the adjustable maternity gown in a separated condition having a design in accordance with the present invention;

FIG. 7 shows a left elevation view of the adjustable maternity gown having a design in accordance with the present invention;

FIG. 8 shows another left elevation view of the bottom and top portions of the adjustable maternity gown in a separated condition having a design in accordance with an embodiment of the present invention;

FIG. 9 shows a right perspective view of the adjustable maternity gown in a separated condition having a design in accordance with the present invention; and,

FIG. 10 shows a perspective view of the top portion of the adjustable maternity gown, the front left side shown in an opened condition and the apparel illustrated in use.

The short dash broken lines showing portions of the article throughout the drawings represent stitching and are not part of the claim. The long dash broken lines to include those illustrating the human form in FIG. 10 also form no part of the claimed design.

1 Claim, 10 Drawing Sheets
